UNITED STATES PATENT OFFICE.

FREDERICK JOHNSON AND HARRY SMITH, OF HATFIELD, MISSOURI.

DISCONNECTING DEVICE FOR TELEPHONE-LINES.

No. 892,060.

Specification of Letters Patent. Patented June 30, 1908.

Application filed March 27, 1907. Serial No. 364,787.

To all whom it may concern:

Be it known that we, FREDERICK JOHNSON and HARRY SMITH, citizens of the United States of America, residing at Hatfield, in the county of Harrison and State of Missouri, have invented new and useful Improvements in Disconnecting Devices for Telephone-Lines, of which the following is a specification.

10 This invention relates to disconnecting devices for telephone lines, and one of the principal objects of the same is to provide means for cutting off the current to a telephone in case of an electric storm which 15 would be liable to injure the instrument or the occupants of a house.

Another object of the invention is to provide a simple device which can be quickly operated to disconnect the line wire from the 20 house wire of a telephone by pulling upon a cord attached to a spring actuated contact lever.

These and other objects may be attained by means of the construction illustrated in 25 the accompanying drawing, in which the figure is a perspective view illustrating the construction and arrangement of a disconnecting device made in accordance with our invention.

30 Referring to the drawing for a more particular description of our invention, the numeral 1 designates a telephone line wire, and 2 is a post located at a sufficient distance outside the wall of a house in which the telephone is located. The line wire 1 passes 35 around an insulator 3, secured to the post 2, and thence around a second insulator 4, where the wire terminates. Pivoted to the post 2 by a porcelain or other insulator knob 40 6 is a contact lever 7, said contact lever having an enlarged contact head 8 provided with a depression 9 to contact with the line wire 1. A spring 10 secured to the post 2 at one end and having its opposite end secured 45 to the contact lever 7 serves to hold the lever in contact with the line wire. The house wire 11 is connected to a loop 12 formed in the contact lever 7 and extends through the wall 13 of the house containing the telephone, 50 and is properly connected thereto. At the

upper end of the lever 7 an operating cord 14 is connected to a loop 15, said cord extending through the wall 13 and provided with a ring 16 at its terminal end, within the house.

When for any purpose it is desired to disconnect the telephone line from the house line, the ring 16 is pulled downward to engage a suitable peg or hook 17, thus disconnecting the house wire 11 from the main line wire 1. Upon releasing the ring 16 from the 55 peg 17 the spring 10 returns the lever 7 to contact with the line wire 1, the current then flowing through the contact lever 7, and through the house wire 11 to the instrument inside the house.

60 From the foregoing it will be obvious that a device made in accordance with our invention will be found very useful during electric storms or whenever it is found desirable to cut off communication between the main 70 line and the instrument in the house.

Having thus described our invention, what we claim is:

1. In a device of the character described, a main line connected to a post by insulators, 75 a contact lever pivoted on the post and provided with a contact head adapted to engage the wire at some distance from the post, a house wire connected to said contact lever and extending to the instrument within the 80 house, a spring for holding said contact lever in operative position, and a cord connected to said lever and extending through the wall of the house for throwing said contact lever out of contact with the line wire. 85

2. A contact lever pivotally connected to a post by an insulator, and provided with an enlarged head having a depression to engage a line wire, a spring for holding said lever in contact with said wire, a house wire connected to said lever and a cord for operating said lever against the tension of the spring, 90 substantially as described.

In testimony whereof, we affix our signatures in presence of two witnesses.

FREDERICK JOHNSON.
HARRY SMITH.
